UNITED STATES PATENT OFFICE.

THEODORE A. ELLIOTT, OF CRANFORD, NEW JERSEY.

BOLT-HEAD-TRIMMING MACHINE.

1,102,024.

Specification of Letters Patent. Patented June 30, 1914.

Application filed July 30, 1913. Serial No. 782,003.

To all whom it may concern:

Be it known that I, THEODORE A. ELLIOTT, a citizen of the United States, and a resident of Cranford, in the county of Union and State of New Jersey, have invented certain new and useful Improvements in Bolt-Head-Trimming Machines, of which the following is a specification.

This invention relates to improvements in bolt-head trimming machines, and has for its specific object the removal of the excess metal from the heads of forged bolt blanks. The said heads with the excess metal are made by forging machines, that form the heads at one stroke. It is to be understood that the invention may also be used for other articles that require the removal of similar excess metal and that its construction may be varied without departing from the spirit of the invention, as set forth in the appended claims.

The organization of this invention resembles somewhat the elements of any ordinary press, with coacting elements.

Figure 1 represents a front elevation of a machine exemplifying the invention. Fig. 2 shows a rear view of Fig. 1, Fig. 3 is a top plan view of Fig. 1, Fig. 4 shows a partial top plan view of the machine, Fig. 5 represents a perspective view of some details, Fig. 6 is a vertical section taken as on the line 6, 6 of Fig. 4, Fig. 7 represents a partial perspective view of the machine partially in section, with the feed mechanism omitted, Fig. 8 shows a partial rear view of Fig. 6 partly in section, Fig. 9 is a top view and section of Fig. 8 on the line 9, 9, Fig. 10 shows a partial elevation of the machine and section on the line 10, 10 of Fig. 4, Fig. 11 shows a partial section of Fig. 10 on the line 11, 11, Fig. 12 shows an elevation of the bolt carrier of the machine, Fig. 13 is a top plan view of Fig. 12, Fig. 14 represents a front elevation of a floating frame, Fig. 15 is a top plan view of Fig. 14, Fig. 16 represents a perspective view of a yielding support, Fig. 17 shows a partial section of Fig. 6 on the line 17, 17, Fig. 18 is a front view of Fig. 17, Fig. 19 shows a fragmentary right hand side view of Fig. 6 looking in the direction of the arrow B, Fig. 20 shows a top plan view and section of Fig. 19 on the line 20, 20, Fig. 21 represents a section of Fig. 4 on the line 21, 21, Fig. 22 represents some of the elements of Fig. 21 in a changed

position, Fig. 23 shows an elevation of a modified detail, Fig. 24 represents a top plan view of Fig. 23, Fig. 24^a shows a section of Fig. 23 on the line 24^a, 24^a, Fig. 25 represents a perspective view of a square headed bolt blank with the flash, Fig. 26 shows a button headed bolt blank including the excess metal, Fig. 27 shows a perspective view of a pair of top shear blades, and Figs. 28 and 29 represent perspective views of a pair of trimming tools.

The invention is represented with a frame designated in its entirety by the numeral 20 and comprises the columns 21, connected by the upper cross tie 22, and the base 23. A tie piece 24 connects the columns 21. Secondary columns 25 are formed with the columns 21, and a table 26 connects the columns 21, 25 and tie piece 24. Guide strips 27 are formed with the columns 21. Journal boxes 28 with caps 29 that support the driving shaft 29 are formed with the columns 21. The driving shaft 29 carries the pinion 30 at one end thereof and at the other end it carries the fly wheel 31, the tight pulley 32 and the loose pulley 33. In the columns 21 are formed journal boxes each with an inverted cap 35, against which latter bears a key piece 36 supported in openings in said columns. Screws 38 maintain the key pieces 36 in proper position. With the cross tie 22 is formed a journal box with the cap 39 held in place by means of the bolts 40. A crank shaft 42 with the arms 43 and crank pins 44 is supported in the three journal boxes 35 just described. A spur gear 45 fastened to one end of the shaft 42 meshes with the pinion 30 on the driving shaft 29. At the other end of the crank shaft 42 is fastened the spur gear 46. On the rear faces of the columns 21 and adjacent to their upper ends are bolted journal boxes 50 with the caps 51, which support the cross shaft 52. A spur gear 53 fastened on said cross shaft meshes with the spur gear 46. A bevel gear 54 is also fastened to the cross shaft 52. A facing 60 is formed with the frame 20 and which supports a guard casing 61, with which are formed journal bearings 62 and 63. A cross rail 65 having the journal bearings 66, 67 is bolted to the column 21. A vertical shaft 68 has its lower end journaled in the journal bearing 62 and its upper end is journaled in the bearing 66. A bevel gear 72 is fastened to the shaft 68 110

and meshes with the bevel gear 54. To the lower end of the shaft 68 is fastened a crank arm 75 from which extends a pin 76, and on the latter is journaled a roller 77. 5 A spindle 80 has its lower end journaled in a bearing 81 in the base 23 of the frame, and its upper end is journaled in a bearing 63 of the guard casing 61. A disk 82 with the radial slots 83 and having formed there- 10 with the spur gear 84 is fastened to the spindle 80. A central column 85 with the central aperture 86 and foot 87 is bolted to the base 23 by means of the bolts 88. A bed plate 89 is bolted to the column 85 by means 15 of the bolts 90. A carrier drum comprising the upper portion 92 and the lower portion 93 is journaled on the column 85. The portions 92 and 93 are connected by the bolts 94. The said portion 93 has formed there- 20 with teeth 95 which latter mesh with the spur gear 84. Pairs of supporting fingers 100 are carried by the portion 92 of said drum and are fastened thereto by means of the screws 101, and clearance spaces in- 25 dicated by the numeral 102 allow the insertion of bolt blanks to be afterward de- scribed. In each of the clearance spaces 102 there is adjustably positioned a yielding support, comprising the frame 105 with the 30 split base 106 and the upper shelf 107. A tapered pin 108 with the threaded end 109 bears between the accompanying faces of the split base 106. A nut 110 on the threaded end 109 allows the operator to separate the 35 members of the split base, so that they can impinge against longitudinal guide edges 111 formed with the portion 92 of the drum, and thereby position the yielding supports in proper place. A table 112 has extending 40 therefrom the shank 113 which registers with an opening in the shelf 107, and a spring 114 encircles the shank 113 and bears between the lower face of the table 112 and the upper face of the shelf 107. A collar 45 115 is fastened to the shank 113.

The bed plate 89 has extending therefrom the vertical leg 116, which latter has formed therewith the annular cavity 117 with the flat runways 118, and a depending annular 50 opening 119 extends from the cavity 117 through the said bed plate 89. Single clamp blocks 122, 123 are connected to the said vertical leg 116 by means of the bolts 124, and a double clamp block 125 is bolted to 55 a projection 126 extending from said leg 116 by means of the bolt 127. A pair of strippers 129 and 130 extend from the vertical leg 116 in alinement with the opening 119. A burring block 135 with inclined top faces 60 136 is seated in the double clamp block 125, and is held in place by means of the screw 137, its upper surfaces being on the same level with the runways 118. A column 138 has formed therewith the flange 139 and the 65 foot 140, which latter bears on the facing

60 and is bolted thereto by means of the bolt 141. Bolts 142 connect the flange 139 with one of the auxiliary columns 25. A burring block 143 with inclined top faces 144 is supported and seated in the column 138, being fastened in position by means of the screw 145, the upper surface of the block 143 being on the same level with the runways 118. A pair of burring blocks 150 each with inclined top faces 151 and the shanks 154 are supported in the vertical leg 116 of the bed plate 89. Their top faces are located on a level with the runways 118 and are on opposite sides of the opening 119.

In the vertical leg 116 of the bed plate 89 are formed keyways 155, which hold splines 156 having formed therewith the upper projecting portions 157. Keyways similar to the keyways 155 are formed in the single clamp blocks 122, 123 and in the double clamp blocks 125. The latter keyways have fastened thereto splines similar to 156. Between the said vertical leg 116 and the blocks 122, 123 and 125 are located trimming dies indicated in their entirety by the numeral 160. The dies 160 bear on the bed plate 89 and have formed in their opposite sides keyways 161, that adjustably engage the splines 156. Shims 165 are positioned in the keyways 161 and lock the splines 156 with the dies 160. By varying the thickness and locations of the shims 165 the said dies 160 can be latterly adjusted, to vary the distance between the cutting edges thereof. The said dies are shown with the top 100 faces 166, the cutting edges 167 and inside faces 168.

Gibs 170 are bolted to the columns 21 and with the guide strips 27 form guides for the main slide 171, the latter having formed therewith the cavities 172. Clamp caps 173 are bolted to the main slide 171 and secure in each of said cavities a pair of shear blades indicated in their entirety by the numeral 175. The shear blades are represented with 110 the cutting edges 176, longitudinal faces 177 and 178. The accompanying faces 177 of each pair of shear blades have interposed between them the shims 179, to enable adjustment between the cutting edges 176, so that 115 the latter can properly coöperate with the cutting edges 167 of the trimming dies 160. Shims not shown are also placed in the cavities 172, and bear against the faces 178 to coact with the shims 179. A lug 185 extends 120 from the front face of the main slide 171 and a perforated boss 186 is formed with one of the clamp blocks 173. A punch 187 is held in the perforation of boss 186, by means of the set screw 188 and its upper 125 face abuts against the lower face of the lug 185. From the rear face of the slide 171 extends the partially perforated lug 192 in which is secured the punch 193, by means of the set screw 194. Connecting rods 195 130

are pinned at their lower ends to the main slide 171 by means of the pins 196. The upper ends of the said connecting rods are supported on the crank pins 44.

5 On the shaft 68 is secured the cam 200. In the bearing 67 is journaled a sleeve 201 having formed therewith the arm 202 and to which is splined the spindle 203 by means of the spline 204. On the spindle 203 is adjustably fastened the thrust collar 205 by means of the set screw 206. A hanger 207 extends from the cross rail 65 and has extending therefrom a pin 208 on which is fulcrumed the rock lever 209. The latter at one 10 end carries the pin 212 on which is journaled the roller 213, that is engaged by the cam 200. The other end of the rock lever 209 carries the pin 214 on which is supported the thrust sleeve 215 which latter is guided on 15 the spindle 203. To the lower end of the spindle 203 is secured the turning tool 216 having the fingers 217.

A hinge pin 220 extends from the cross rail 65 and has fulcrumed thereon the boss 221 with the arm 222. A pin 223 on said arm has journaled thereon the roller 224 in about the central portion thereof. A pin 225 connects the arm 222 with one end of the link 226. The other end of the link 226 is 20 pinned to the arm 202 by means of the pin 228. A boss 230 is journaled on the pin 220 and has extending therefrom the arm 231, the end of which latter carries a pin 232 for the roller 233. A bolt 234 connects the arms 222 and 231. A cam 235 is fastened to the vertical shaft 68 and coacts with the arm 222, and a second cam 236 on said shaft coacts with the arm 231.

A hollow bracket 242 bears on and is 25 bolted to base 23 of the frame of the machine by the bolt 243, and has extending from one side a flange 244, which is bolted to one of the auxiliary columns 25, by means of the bolts 245. The bracket 242 is formed 30 at its upper end with the roof 246 and in one of its side walls is formed the opening 247. Ribs 248, 249 extend from the body of the bracket and the rib 248 carries the bolts 250. A chute with the roof 255, runways 253, 35 liners 254 and the depending side 256, with the curved openings 257 is adjustably secured to the rib 248, by means of the bolts 250. From the roof 246 of said hollow bracket extends the boss 258 in which is secured the pin 260. A rock lever with the arms 263 and 264 is fulcrumed on the pin 260. At the end of the arm 263 is located the pin 265 on which is pinned the eye 266 of the shifter rod 267 having the shoulder 40 268. Jam nuts 269 are carried on the rod 267. A guide bracket 270 is bolted to the slide 171 and has a guide opening 272 for the rod 267.

The arm 264 carries the pin 275 on which 45 is suspended a spring connection, compris-

ing a frame piece 276 with the legs 277, the latter being joined by the tubular end portion 278. A rod 282 extends through the tubular portion 278 into a cavity 279 in the frame piece 276. A collar 283 is fastened to the rod 282 and a spring 284 bears between said collar and the said tubular portion 278. A short shaft 285 is journaled in the walls of the bracket 242 and has fastened thereto one end of the arm 286. The other end of the latter has fastened thereto a pin 287 which engages the lower end of the rod 282. An arm 290 practically at right angles to the arm 286 has one end fastened to the short shaft 285, and the other end thereof engages a pin 291 carried on a floating frame having the frame sides 292 and 293. End cross pins 294 and 295 connect the said frame sides 292 and 293. A link 296 connects the pin 295 with a pin 297 supported in the bracket 242. On the pin 294 is supported a bolt carrier designated in its entirety by the numeral 300. The carrier comprises the head 301 which has formed therewith the arm 302 and the leg 303. A cavity 304 with an opening at its lower end, in the carrier has connected thereto the guide strips 305 and 306. A rising runway 311 is bolted to the column 138 by means of the bolt 312. A guide plate 313 is bolted to the clamp block 314 by means of the bolt 312.

In Figs. 23 and 24 a modified form of supporting fingers is indicated at 325, 326, carried on the portion 92 of the carrier drum. The fingers are grouped in pairs as already described. The fingers 325 are beveled at their upper ends 327 and are fastened to the portion 92 by means of the screws 330. Each finger 326 is beveled at its upper end 331 and has formed therein the longitudinal V shaped groove in one of its edges, to center the bolt blank located between the fingers. The fingers 326 are each connected to the portion 92 of the carrier drum by means of a pivot bolt 333 at the lower end thereof, and a guide screw 334 engages an elongated opening 335 in said finger and is in threaded engagement with said portion 92. A spring 340 carried on the drum bears against the upper end of the finger, to position the finger so that it will bear against the bolt blank to keep it in proper position.

To operate the machine power is transmitted to the pulley 32 by a belt not shown, which turns the driving shaft 29. The pinion 30 on the shaft 29 turns the spur gear 45 and with it the crank shaft 42. The main slide 171 is reciprocated by means of the connecting rods 195, which latter are actuated by the crank shaft 42. The shear blades 175, the punches 187 and 193 and guide bracket 270 reciprocate with said main slide 171. The rock lever having the arms 263, 264 is rocked by the reciprocations of

the guide bracket 270 and thereby the frame piece 276 is moved up and down, which in turn oscillates the arm 286. The arm 290 is thereby oscillated and causes the floating frame having the sides 292 and 293 to move to and fro. The bolt carrier 300 is thereby moved by the said floating frame approximately in the arc of a circle. The bolt blanks 350 with the heads 351 having the flash 352 or the bolt blank 353 with the heads 354 having the excess metal 355 are delivered by gravity from the chute 255 to the said bolt carrier 300, which locates them between the supporting fingers 100 and on the table 112. Each reciprocation of the main slide 171 locates the bolt carrier 300 in proper position to receive a bolt blank. The spur gear 46 by reason of the rotations of the crank shaft 42 rotates the gear 53 and thereby the shaft 52. The rotations of the latter are transmitted to the vertical shaft 68 by the gears 54 and 72. The crank arm 75 during its revolutions coacts with the slots 83 causing the disk 82 to rotate, and thereby rotation is given to the spur gear 84. The teeth 95 meshing with the teeth of the gear 84, cause the drum having the lower portion 93 and the upper portion 92, to rotate about the central column 85, and thereby the supporting fingers 100 with their accompanying yielding supports having the tables 111, are revolved intermittently.

Referring particularly to Figs. 7 and 11, the bolt blank is indicated at A as delivered from the bolt carrier 300 upon the table 112. The drum having the portions 92, 93 rotates and carries the bolt blank to the position indicated at A¹, and the shear blades 175 at practically the same time rise and allow the bolt blank to attain the latter position. The bolt blank is now still supported on the yielding support with the table 112 and between the faces 168 of the trimming dies 160. The main slide 171 now descends, and the cutting edges 176 of said shear blades 175 descend, the cutting edges straddling a pair of the sides of the head of the bolt blank and the flash or excess metal is sheared off, the bolt descending by reason of the flexible appurtenances connected with the table 112. Should the bolt blank be positioned between the trimming dies 160 so that the planes of the sides of the head of bolt blank are located in position making angles with the cutting edges 176 of the shear blades 175, the coaction of the latter with the flexibility of the support causes the bolt blank to be properly positioned with the sides of the head parallel to the said cutting edges 176 of the shear blades. The slide 171 now rises and the drum attains a second intermittent position of its revolution and the partially sheared bolt blank is moved to the position indicated at A², between the

burring blocks 150 shown enlarged in Fig. 21, and in which position any slight bur or fin 360 that may have resulted from the shearing of the flash 356 or excess metal 355 is disposed of as follows: The slide 171 with the punches 187, 193 descend and the punch 193 bearing upon the upper face of the head of the bolt blank, causes the bur or fin 360 to be curled in and pressed against the lower face of the bolt blank head, by reason of the coaction of the burring blocks 150. The main slide 171 rises again and the drum makes another intermittent movement of its revolution, and carries the partially sheared and burred bolt blank to the position indicated at A³, which is plainly shown in Figs. 4 and 7. In this last location the head of the bolt blank is in proper alignment to be engaged by the fingers 217 of the turning tool 216. The sleeve 215 descends by virtue of the rotations of the vertical shaft 68, and the coöperation of the cam 200, and rock lever 209. Upon the descent of the sleeve 215, the turning tool 216 descends by gravity and the fingers 217 engage the sides of the bolt head. The further rotation of the shaft 68 causes the coaction of the cam 235 and arm 222, which with the link 226 and sleeve 201 turns the tool 216 axially through an arc of 90 degrees, and by reason of the co-action of the fingers 217 with the sides of the bolt head, the bolt is also axially turned through an arc of 90 degrees. Upon the further rotation of the shaft 68 the turning tool 216 rises to clear the fingers 217 from the head of the bolt blank. The drum now again makes a partial movement of its revolution, and carries the blank to the position of rest indicated at A⁴. The drum again makes a partial movement of its revolution and carries the bolt blank to the position indicated at A⁵, the main slide 171 at the same time rising to the end of its upstroke. In this position the bolt blank is brought between the faces 168 of the second pair of trimming dies 160. The main slide descends and the second pair of shear blades 175 shears off the flash 352 or excess metal 355, still remaining adjacent to the other faces of the head of the bolt blank. The main slide 171 again rises while the drum makes another partial movement of its revolution and carries the bolt blank in alignment with the burring blocks 135 and 143 indicated at A⁶. Next the main slide 171 descends and forces the punch 187 against the top surface of the head of the bolt blank, and causes the lower surfaces of the head of the bolt blank to bear against the burring blocks 135, 143 by virtue of which any burs or fins resulting from the second shearing operation are curled under and pressed against the under side of the head of the bolt blank. The main slide 171 again rises and the drum again makes an intermittent movement and delivers the

trimmed and burred bolt blank to the rising discharging runway 311 and its head at the same time bears against the guide plate 313, thereby raising the barrel of the bolt blank 5 clear of the table 112. The bolt blank then swings clear of the supporting fingers 100, by reason of the bolt blank hanging with one side of its head supported on the runways 311, and the opposite side of the head bearing 10 against the guide plate 313. The bolt is discharged from its latter position, by the next succeeding bolt blank when the latter travels up on said rising runway 311, at the next succeeding partial rotation of the drum, 15 when the supporting fingers 100 will be positioned at A⁷, which completes the cycle of operations. It will be understood that the main slide 171 makes one double stroke for each intermittent partial revolution of the 20 drum. The office of the aperture 86 in the central column 85 is to carry away the flash or excess metal, resulting from the trimming of the heads of the bolt blanks.

Having described my invention what I 25 desire to secure by Letters Patent and claim is:

1. In a machine the combination of a pair of accompanying dies, a pair of accompanying shear blades for said dies, to remove 30 the flash or excess metal from a pair of sides of a bolt blank during a reciprocation of the shear blades.

2. In a machine, the combination of a pair of dies, a pair of shear blades coacting 35 with the dies, a second pair of dies, and pair of shear blades for the latter dies and means to feed bolt blanks to the first pair of dies and shear blades, to remove excess metal from a pair of sides of a bolt blank, 40 and means to position the bolt blank for the second pair of dies and their shear blades, to remove the excess metal from a second pair of sides of the bolt blank.

3. In a machine the combination of means 45 to trim the head of a bolt blank to remove the flash or excess metal formed during the formation of the head thereof and means to obliterate the bur resulting from the removal of said flash or excess metal.

50 4. In a machine the combination of means to trim the head of a bolt blank on a pair of opposite sides of said head to remove the flash or excess metal, means to obliterate the bur resulting from the removal of said flash or 55 excess metal, means to trim a second pair of sides of said head to remove the flash or excess metal accompanying the latter pair of sides and means to obliterate the bur resulting from the removal of the flash or 60 excess metal from the second pair of sides.

55 5. In a machine the combination of means to trim the head of a bolt blank on a pair of opposite sides of said head to remove the flash or excess metal, means to obliterate the bur resulting from the removal of said 65

flash or excess metal, means to partially rotate the bolt blank, means to trim a second pair of sides of said head after said partial rotation and means to obliterate the bur resulting from the removal of the flash or 70 excess metal from the second pair of sides.

6. In a machine the combination of a pair of trimming dies, a pair of shear blades coacting with the dies to trim a pair of sides of the head of a bolt blank, a pair of burring blocks and a coacting punch in the machine, means to locate the head of the bolt blanks in proper position for the burring blocks and punch, means to actuate the punch to obliterate the bur from the head of the bolt blank resulting from the trimming thereof, means to turn the bolt blank, a second pair of shear blades and a pair of dies coacting therewith to operate on the bolt blank in its turned position to trim another pair of sides of said head, and a second pair of burring blocks and a punch coacting with the latter to obliterate the bur from the head resulting from the operation of the second pair of 80 trimming dies and shear blades.

7. In a machine the combination of a drum, means to intermittently rotate the drum, means to yieldingly support bolt blanks on the drum, a pair of trimming dies coacting with the drum in one position thereof, a punch coacting with the burring blocks to obliterate the bur resulting from the trimming of the bolt blank, means to give the bolt blank a partial rotation in another position of the drum, a second pair of trimming dies, and a second pair of shear blades coacting with the latter dies to trim the bolt blank in another position of the drum, a second pair of burring blocks and a punch coacting therewith to obliterate the bur caused by the trimming resulting from the second pair of trimming dies and their shear blades at a further changed position of the drum.

8. In a machine the combination of a pair of trimming dies, a pair of shear blades coacting with the dies to remove the flash from a pair of sides of the head of a bolt blank, a pair of burring blocks and a coacting punch in the machine, means to locate the head of the bolt blanks in proper position for the burring blocks and punch, means to actuate the punch to obliterate the bur from the head of the bolt blank resulting from the trimming thereof, means to turn the bolt blank, a second pair of shear blades and pair of dies coacting therewith to operate on the bolt blank in its turned position to remove further flash therefrom and a second pair of burring blocks and a punch coacting with the latter to obliterate the bur from the head resulting from the operation of the second pair of trimming dies and shear blades.

9. In a machine the combination of a drum, means to intermittently rotate the drum, means to flexibly support bolt blanks on the drum, a pair of trimming dies coacting with the drum in one position thereof, a punch coacting with the burring blocks to obliterate the bur resulting from the removal of the flash of the bolt blank, means to give the bolt blank, a partial rotation in another position of the drum, a second pair of trimming dies, and a second pair of shear blades coacting with the latter dies to remove flash from the bolt blank in another position of the drum, a second pair of burring blocks and a punch coacting therewith to obliterate the bur resulting from the removal of the flash with the second pair of trimming dies and their shear blades at a further changed position of the drum.
10. In a machine the combination of a frame, a hollow bracket having an opening in one side wall thereof fastened thereto, a floating frame in said hollow bracket, a reciprocating element in the machine, connections between said element and the floating frame to impart a movement to the floating frame, a bolt carrier suspended on the floating frame, a chute having runways connected to the hollow bracket and registering with the opening in the side wall thereof.
11. In a machine the combination of a frame, a hollow bracket having an opening in one side wall thereof fastened thereto, a floating frame in said hollow bracket, a reciprocating element in the machine, connections between said element and the floating frame to impart a curvilinear movement to the floating frame, a bolt carrier suspended on the floating frame, a chute having runways adjustably connected to the hollow bracket and registering with the opening in the side wall thereof, the chute positioned to incline its runways.
12. In a machine the combination of a carrier drum, means to intermittently rotate the drum, pairs of supporting fingers carried on the drum, and a yielding support located between each pair of fingers and secured to the drum.
13. In a machine the combination of a carrier drum, means to intermittently rotate the drum, pairs of supporting fingers carried by the drum and a yielding support located between each pair of fingers and adjustably connected to the drum.
14. In a machine the combination of a central column, a carrier drum having teeth at one portion thereof journaled on the column, a rotating shaft journaled in the machine, a crank arm fastened to the shaft, a pin extending from the arm, a roller journaled on the pin, a spindle journaled adjacent to the shaft, a disk having radial slots and a spur gear formed therewith fastened to said spindle, the said slots consecutively

engaging the said roller and the spur gear of the disk meshing with the teeth of the carrier drum.

15. In a machine the combination of a central column, a carrier drum journaled thereon, means to intermittently rotate the drum, a bed plate secured to the upper end of the central column, a vertical leg having an annular cavity with runways and a depending annular opening formed with the bed plate, means on the drum to support bolt blanks, means coacting with the drum to trim the bolt head, the bolt blank traveling through the said annular cavity and opening during the operation of the machine.

16. In a machine the combination of a carrier drum, means to support bolt blanks on the drum, a turning tool for the machine adapted to engage the head of a bolt blank, means to oscillate the turning tool and means to axially reciprocate said tool.

17. In a machine the combination of a turning tool, a rotary shaft journaled in the machine, a cam carried on the shaft, a linked connection coacting between the cam and turning tool to oscillate the latter, a second cam on the rotary shaft and connecting means between the latter cam and the turning tool to axially reciprocate the latter.

18. In a machine of the character described the combination of a rotary shaft, a pair of coacting cams fastened to said shaft, a hinge pin in the machine, an arm with one end supported on the hinge pin, a turning tool, a sleeve splined to the turning tool, an arm extending from the sleeve, a link with one end pinned to the latter arm and the other end thereof pinned to the arm that has one end supported on the hinge pin, a roller journaled on the latter arm in the path of one of said cams, a second arm supported on the hinge pin and fastened to the first arm that is supported on said hinge pin, a roller journaled on the latter arm in the path of the second cam, the cams with their coacting elements oscillating the turning tool.

19. In a machine of the character described the combination of a rotary shaft, a cam secured to the shaft, a rock lever fulcrumed in the machine, a roller journaled at one end of the lever engaged by said cam, a pin secured to the other end of the lever, a turning tool guided in the machine, a collar fastened to the turning tool, a thrust sleeve slidably supported on the tool and bearing at its upstroke against said collar, the said sleeve also hinged to the pin secured to the said lever, the combination of elements coacting to produce upstrokes for the turning tool.

20. In a machine the combination of a frame, a bed plate supported in the frame having a vertical leg, two pairs of trim-

ming dies supported on said bed plate, clamp blocks bearing on the bed plate, bolts connecting the vertical leg of the bed plate and said clamp blocks to clamp the trimming dies in place, a rotating carrier drum journaled in the machine, means on the drum to support bolt blanks, a main reciprocating slide for the machine, means to reciprocate the slide, and a pair of shear blades for each pair of trimming dies carried on the slide.

21. In a machine the combination of a frame, a bed plate supported in the frame having a vertical leg, two pair of trimming dies supported on said bed plate, clamp blocks bearing on the bed plate, bolts connecting the vertical leg of the bed plate and said clamp blocks to clamp the trimming dies in place, a reciprocating slide guided 20 in the frame and shear blades carried on the slide coacting with the trimming dies.

22. In a machine the combination of a movable element to support an object to be operated upon, dies supported in the machine, a reciprocating element in the machine, shear blades connected to the latter element coacting with the dies and means in the machine to prevent the dislodgment of the object operated upon during the up- 30 strokes of the shear blades.

23. In a machine the combination of a frame, a bed plate supported in the frame, a carrier drum journaled in the frame, means to support an object to be operated upon 35 connected to the drum, trimming dies supported on the bed plate, a reciprocating slide guided in the frame, shear blades connected to the slide coacting with the trimming dies, and strippers positioned in the machine 40 to prevent the dislodgment of the object operated upon during the upstrokes of the shear blades.

24. In a machine the combination of a pair of trimming dies, means to vary the 45 distance between the cutting edges of the dies, a movable element in the machine, a pair of shear blades connected to said element and coacting with the dies.

25. In a machine the combination of a pair of trimming dies, means to vary the 50 distance between the cutting edges of the dies, a movable element in the machine, a pair of shear blades connected to said element and means to vary the distance between the cutting edges of the shear blades.

26. In a machine the combination of a bed plate, a pair of splines extending from the bed plate, a pair of trimming dies having keyways formed thereon to register with 55 said splines, shims in the keyways to coact with the splines to position the trimming dies varying distances apart, a movable element in the machine, a pair of shear blades adjustably connected to the said element, and

shims between the shear blades to vary the 65 distance between their cutting edges.

27. In a machine the combination of a reciprocating element, a chute for an object to be operated upon in the machine, a bracket in the machine having an opening 70 registering with said chute, a rock lever fulcrumed on the bracket, a connection between one end of the rock lever and the reciprocating element, a pivot fulcrumed in said bracket, a pair of arms practically at right angles 75 to each other fastened to said pivot, a pair of frame sides pinned to one of said arms, a flexible connection between the other arm and the rock lever, a link with one end pinned to the frame sides and the other end thereof pinned to said bracket and a carrier for an object to be operated upon carried by said frame sides.

28. In a machine the combination of a chute for objects to be operated upon, a carrier positioned at the discharge end of the chute to receive said objects, means to move the carrier to and fro at right angles to the chute, the carrier comprising a head to connect it to a moving element, the said 90 head having a cavity with an opening at its lower end and a leg extending from below said opening.

29. In a machine the combination of a driving shaft, means to rotate the shaft at 95 one end thereof, a pinion fastened to the other end of the shaft, a crank shaft journaled in the machine, a gear fastened to one end of the crank shaft meshing with said pinion, connecting rods with one end of 100 each supported by the crank shaft, a main slide in the machine connected to the other ends of the connecting rods, a cross shaft journaled in the machine, a gear fastened to one end of the cross shaft, a gear on the 105 crank shaft meshing with the gear on the cross shaft, a bevel gear on the cross shaft, a vertical shaft journaled in the machine, a bevel gear on the latter shaft meshing with the bevel gear on the cross shaft, a carrier 110 drum for an object to be operated upon journaled in the machine, connections between said drum and said vertical shaft, a turning tool in the machine and connections 115 between the vertical shaft and the turning tool.

30. In a machine for trimming bolt blanks the combination of a rotating carrier drum, means to remove excess metal from the heads of the bolt blanks operated upon, pairs of 120 supporting fingers on the drum, a yielding support on the drum between each pair of fingers for the bottom end of the accompanying bolt blanks to bear on, a rising discharging runway and guide plate positioned 125 in the machine to support the bolt blanks after having been operated upon, the two latter elements swinging the bolt blanks

clear of the yielding supports and then discharging them from the machine.

31. In a machine of the character described the combination of a rotating carrier drum, means to remove excess metal from the heads of bolt blanks operated upon, pairs of supporting fingers for the drum, one of each pair of fingers securely fastened to the drum, one finger of each pair pivoted at one end to the drum and the other end thereof guided to bear against a bolt blank located between the pair of fingers.

32. In a machine of the character described the combination of a rotating carrier drum, means to remove excess metal from the head of bolt blanks operated upon, pairs of supporting fingers for the drum, one of each pair of fingers securely fastened to the drum, one finger of each pair pivoted at one end to the drum and having an elongated opening in about its central portion, a guide screw on the drum registering with said elongated opening and a spring with one end fastened to the carrier

drum and the other end bearing against the pivoted finger.

33. In a machine of the character described the combination of a pair of dies, a pair of shear blades for the dies, means to reciprocate the shear blades and means to position a bolt blank relatively to the dies and shear blades to remove excess metal from the head of a bolt blank.

34. In a machine of the character described the combination of two pair of dies, a pair of shear blades for each pair of dies, means to reciprocate the shear blades and means to position bolt blanks relatively to the dies and shear blades to remove excess metal from the heads of the bolt blanks.

Signed in the borough of Manhattan in the county of New York and State of New York, this 29th day of July A. D. 1913.

THEODORE A. ELLIOTT.
